UNITED STATES PATENT OFFICE.

WILLIAM ROBERT BELDAM, OF LONDON, ENGLAND.

SEMIMETALLIC PACKING.

Application filed July 13, 1920. Serial No. 396,030.

To all whom it may concern:

Be it known that I, WILLIAM ROBERT BELDAM, a subject of the King of England, residing in London, England, have invented ⁵ certain new and useful Improvements in Semimetallic Packings, of which the following is a specification.

This invention is for improvements in or relating to semi-metallic packings, that is to ¹⁰ say packings comprising in combination a flexible composition strip formed with an open channel extending inwardly from one face of the strip and longitudinally thereof, and metal filling blocks disposed in the channel. The flexible strip may be of the usual asbestos composition of known type.

According to the present invention in such a packing the metal filling blocks together substantially fill the channels and each of ²⁰ the blocks is formed with a spike or spikes driven into the bottom wall of the channel to retain the blocks in position within the channel.

Preferably the channel is formed with ²⁵ side walls which are inclined outwardly from the lateral margins of the bottom wall, and those surfaces of each block which engage with the walls of the channel are shaped to conform to the configuration of the walls.

A feature of the invention comprises a filling block the cross-section of which, in a plane transverse to the length of the channel, is such as either to fill substantially half the ³⁵ cross-section of the channel or to fill substantially the whole cross-section thereof.

According to another feature of the invention a block is formed with a middle portion of such cross-section as substantially to ⁴⁰ fill the whole cross-section of the channel and with projections on each side of the middle portion to extend longitudinally of the channel on opposite sides of the centre line thereof each projection being such as to fill substantially half the cross-section of the channel, and with a spike extending only from the middle portion. Thus, the block is stepped in cross-section.

Other features of the invention comprise ⁴⁵ the formation of the filling blocks with a shoulder to be seated on the bottom wall of the channel, and by the curving of the bearing faces of the blocks and the rounding of

the butting sides of the blocks as will be more fully described hereinafter. ⁵⁵

Some preferred forms of the invention will now be described in detail by way of example only and with the aid of the accompanying drawings in which—

Figure 1 is a perspective view of a portion ⁶⁰ of the flexible strip;

Figure 2 is a similar view of the strip and filling blocks curved round to conform to the part to which it is to be applied;

Figure 3 shows the arrangement of the ⁶⁵ blocks shown in Figure 2 in their relative positions when the strip is laid flat;

Figure 4 is a section on the line IV—IV of Figure 3, and

Figures 5, 6 and 7 illustrate respectively ⁷⁰ modified forms of filling block.

As shown in Figure 1, the flexible strip 1 is formed with a channel of which the side walls slope inwardly towards a flat bottom wall. ⁷⁵

In Figures 2, 3 and 4 filling blocks according to one form are illustrated and comprise a plurality of similar blocks 2 each formed with a central spike 3. Each block is such as to fill substantially half the cross-section of ⁸⁰ the channel in the strip as shown clearly in Figures 2 and 4, and has a sloping face 4 to engage a side wall of the channel.

The bearing surface 5 of each block is dished as shown, in the direction which will ⁸⁵ be that of the length of the channel when the block is in position. The dishing or curvature of the bearing faces is not necessarily such as to conform to one particular curvature of a part with which the packing is to ⁹⁰ be employed but may be approximately suited to several different degrees of curvature. In use, it is found that if the faces 5 do not actually bear evenly on the periphery of the part with which they will be in contact, they ⁹⁵ will quickly wear down so as to bear evenly on that part owing to the fact that the blocks are made of metal which is less hard than is the part upon which they bear.

The outer corners 6 of the butting sides ¹⁰⁰ of adjacent blocks are also rounded to render the studded band flexible. The rounding of the shoulders is preferably such as to accommodate a degree of curvature of the smallest diameter for which the packing is ¹⁰⁵ likely to be used.

It will be seen that in the construction illustrated the spikes 3 extend from the central portion only of the blocks, leaving shouldered surfaces 7 which will seat on the bottom wall of the channel when the spikes have been driven home.

In a modified form of block shown in Figure 5, two spikes 3 are provided and the block is of such cross-section as to substantially fill the whole cross-section of the channel. A surface 7 corresponding to the shouldered surfaces 7 in Figures 2, 3 and 4, is formed between the spikes 3. The block in this case is similarly formed with a dished surface 5 and rounded corners 6.

In the modification shown in Figure 6, the whole block is carried down to a pointed or spiked extremity 3 without the formation of any shouldered surface corresponding to the surface 7 previously described. This block also has a dished bearing surface 5 and rounded corners 6.

Obviously the blocks illustrated in Figures 5 and 6 could each be formed in two portions to lie side by side within the channel in a similar manner to the blocks described in connection with Figures 2, 3 and 4.

In Figure 7 a block, which is stepped in cross-section, is illustrated having a dished bearing surface 5. The middle portion of the block is of such cross-section as substantially to fill the whole of the cross-section of the channel and has two side projections extending from opposite sides of a centre line and of such cross-section as to fill substantially only half of the cross-section of the channel. A spike 3 extends from the middle portion only and shouldered surfaces 7 are formed on each side of the spike and at the inner extremities of the side projections. All the butting corners of such a block are rounded at 6. It is obvious that when a plurality of these blocks are driven into the channel of the strip 1 the side projection of one block will fit in the space afforded between the adjacent side projection of the block next to it and of the wall of the channel so that in the entire length of the strip the channel is substantially filled with metal.

It will be obvious that in addition to the forms described other forms of block could be employed without departing from the spirit of the invention.

What I claim as my invention and desire to secure by Letters Patent is:—

1. A semi-metallic packing, comprising, in combination, a single flexible composition strip having formed therein an open channel extending inwardly from one face of it and longitudinally thereof, and a plurality of similar metal filling blocks positioned in said open channel and together substantially filling the channel, each of said filling blocks being of wedge formation and formed with

at least one spike projecting beyond the main body thereof and driven into the bottom wall of the channel without clenching to retain the blocks in position in the channel.

2. A semi-metallic packing, comprising, in combination, a single flexible composition strip having formed therein an open channel extending inwardly from one face of it and longitudinally thereof, with the side walls of the channel diverging outwardly from the lateral margins of the bottom wall thereof, and a plurality of similar metal filling blocks positioned in said open channel and together substantially filling the channel, each of said filling blocks being formed with at least one spike projecting beyond the main body thereof and driven into the bottom wall of the channel without clenching to retain the blocks in position in the channel, the surfaces of each block which engage the walls of the channel being shaped to conform to the configuration of said walls.

3. A semi-metallic packing comprising in combination a flexible composition strip formed with an open channel extending inwardly from one face of it and longitudinally thereof, and a plurality of metal filling-blocks which together substantially fill the channel, each said block having a middle portion of such cross-section as substantially to fill the whole cross-section of the channel and projections one on each side of the middle portion to extend longitudinally of the channel on opposite sides of the centre line thereof and of such cross-section as to fill substantially half the cross-section of the channel, and at least one spike, for the purpose described.

4. A semi-metallic packing comprising in combination a flexible composition strip formed with an open channel extending inwardly from one face of it and longitudinally thereof, and a plurality of metal filling-blocks which together substantially fill the channel, each said block having a middle portion of such cross-section as substantially to fill the whole cross-section of the channel and projections one on each side of the middle portion to extend longitudinally of the channel on opposite sides of the centre line thereof and of such cross-section as to fill substantially half the cross-section of the channel, and a spike extending only from the middle portion of the block with a shoulder formed at the junction of the root of the tooth and the block.

5. A metal filling block which is for use with a semi-metallic packing comprising an open channeled flexible composition strip and a plurality of similar filling blocks which together substantially fill said channel, said block being of wedge formation and formed with at least one spike thereon.

and with a flat surface which affords a shoulder at its junction with the root of the spike and is of such form as to fit along the bottom wall of the channel.

5. 6. A metal filling-block which is for use with a semi-metallic packing comprising an open channelled flexible composition strip and a plurality of similar filling-blocks which together substantially fill the channel, 10 the said block being of wedge formation and formed with a bearing face which is dished in a direction which will be that of the length of the channel when the block is in position, and provided with a spike adapted 15 to be driven into the flexible composition of the strip without clenching, for the purpose described.

7. A metal filling-block which is for use with a semi-metallic packing comprising a 20 channelled flexible composition strip and a plurality of similar filling-blocks which together substantially fill the channel, the said block being formed with those of its butting corners at the mouth of the channel rounded 25 off, for the purpose described.

8. A metal filling-block which is for use with a semi-metallic packing comprising a channelled flexible composition strip and a plurality of similar filling-blocks which together substantially fill the channel, the 30 said block having a middle portion of such cross-section as substantially to fill the whole cross-section of the channel and projections one on each side of the middle portion to extend longitudinally of the channel 35 on opposite sides of the centre line thereof and of such cross-section as to fill substan-

tially half the cross-section of the channel, and at least one spike adapted to be driven into the flexible body of the packing, for 40 the purpose described.

9. A metal filling-block which is for use with a semi-metallic packing comprising a channelled flexible composition strip and a plurality of similar filling-blocks which together substantially fill the channel, the said 45 block having a middle portion of such cross-section as substantially to fill the whole cross-section of the channel and projections one on each side of the middle portion to extend longitudinally of the channel on opposite sides of the centre line thereof and of such cross-section as to fill substantially half the cross-section of the channel, and a 50 spike extending only from the middle portion of the block, for the purpose described. 55

10. A metallic filling block which is for use with a semi-metallic packing comprising a channelled flexible composition strip and a plurality of similar filling blocks 60 which together substantially fill the channel, the said blocks having a middle portion of such cross section as to substantially fill the whole cross section of the channel, and offset projections one on each side of the middle portion to extend longitudinally of the channel, said projections being of such cross section as to substantially fill half the cross section of the channel, and at least one spike 65 on said block adapted to be driven into the 70 flexible body of the packing, for the purpose described.

In testimony whereof I affix my signature.
WILLIAM ROBERT BELDAM.
